CLAIM

The ornamental design for a flow nozzle, as shown and described.

DESCRIPTION

FIG. 1 is a perspective view of a flow nozzle showing our new design;

FIG. 2 is a side elevational view, taken from the left hand side of FIG. 1;

FIG. 3 is a side elevational view, taken from a right hand side of FIG. 1;

FIG. 4 is a side rotated elevational view, taken from the left hand, rotated side of FIG. 1;

FIG. 5 is a side rotated elevational view, taken from the right hand, rotated side of FIG. 1;

FIG. 6 is an elevated view of the front thereof; and,

FIG. 7 is an elevational view of the rear thereof.
